DESIGN FOR A HANDLE FOR FORKS, SPOONS, AND SIMILAR ARTICLES.

No. 37,990.

Specification for Design.

Patented May 8, 1906.

Application filed March 31, 1906. Serial No. 309,226. Term of patent 7 years.

To all whom it may concern:

Be it known that I, JOHN LEECH, a citizen of the United States, residing at Bridgeport, county of Fairfield, State of Connecticut, have invented a new, original, and ornamental Design for a Handle for Forks, Spoons, and Similar Articles, of which the following is a specification, reference being had to the accompanying drawing, forming part thereof.

The drawing is a representation of a fork

embodying my novel design, with the outline of a spoon indicated by dotted lines.

What I claim is—

The ornamental design for a handle for forks, spoons and similar articles, as shown.

JOHN LEECH.
